UNITED STATES PATENT OFFICE.

THOMAS G. HITT, OF SEATTLE, WASHINGTON.

FIRECRACKER.

Application filed December 8, 1925. Serial No. 74,066.

This invention relates to improvements in the construction and method of making fire crackers.

One of the objects of this invention, is 5 to provide a fire cracker entirely devoid of end plugs and the like, the explosive matter being folded within a box like container and securely located within a tapered tubular portion.

10 Further objects of this invention will appear from the disclosure in the single sheet of drawings herewith made a part of this application and in the following detailed description.

15 In the drawings,

Fig. 1 illustrates a vertical sectional view of the fire cracker showing the explosive matter and fuse connected thereto within the tapered tubular portion.

20 Fig. 2 represents a perspective view of the box like container for the explosive in partly folded condition.

Fig. 3 illustrates a perspective view of Fig. 2, disclosing the box like container for 25 the explosive folded to a greater degree than disclosed in Fig. 2.

Figs. 4 and 5 represent perspective views of the box like container for the explosive in further stages of folding.

30 Numeral 1 designates a tapered tubular portion adapted to hold securely therein, at a point midway between its ends, 2 and 3, a bag or package with explosive matter 4, the bag 5 being preferably formed from a single sheet of suitable material having a slot or slit 6 properly located along one edge 7 thereof.

The bag 5 in its folded and completed condition as disclosed in Fig. 5, will obviously 40 include two distinct and separate portions 8 and 9 adapted to fold up from one end of the explosive bag container, the portion 9 being particularly adapted to fold up within the outer layer of the bag while the 45 portion 8 will fold upward along the exterior portion of the bag, thereof, forming an end piece which will aid materially in holding the explosive bag securely within the tapered tubular portion 1. This is brought 50 about from the fact that the folded end por-

tion 8 has a distinct tendency to bear outwardly toward the inside periphery of the tapered tubular portion 1, thereby increasing the frictional resistance within the tubular portion 1.

55 The explosive material 4 is placed within the bag 5, the upper portion of which is sealed in a suitable manner by means of cords 10 or otherwise, after inserting additional explosive material 4, the ends of a 60 fuse 11, the fuse 11 being so positioned in connection with the explosive material 4 that the looped portion 12 is located at a suitable distance beyond one end of the tapered tubular section 1, thereby forming a fuse having 65 a considerably higher degree of efficiency than the fuse at present commonly used in the manufacture of fire crackers.

In lighting or setting the looped end of the fuse as described in this application, it 70 is obvious, that two lighted end portions will find their way into the explosive matter or it may be that one of the ends will become extinguished while the other end will perform the required duty.

75 This invention provides a fire cracker having efficient means for securely folding the explosive matter and its container within a tapered tubular portion, which portion 1, may be made of any suitable material, the 80 tapered effect making it possible to more securely bind the explosive matter in its proper position somewhere between the two ends of the tubular tapered portion.

85 What I claim is:

1. A firecracker having a truncated tubular tapered body portion of substantially uniform thickness throughout its length, a charge of explosive matter securely wedged within the tapered body portion at a point 90 between its ends.

2. A firecracker having a truncated tubular tapered body portion of substantially uniform thickness throughout its length, a charge of explosive matter securely wedged within the tapered body portion at a point 95 between its ends, the explosive matter being enclosed in a bag.

In testimony whereof I affix my signature.
THOMAS G. HITT.
